UNITED STATES PATENT OFFICE.

JOHN FIELDING, OF NORTH PROVIDENCE, RHODE ISLAND, ASSIGNEE OF ONE-HALF TO
JOSEPH P. WHITAKER, OF APPONAUG, RHODE ISLAND.

SAFETY CATCH.

Application filed February 13, 1928. Serial No. 253,968.

This invention relates to a safety catch for securing in position pin stems of the type more particularly applied to jewelry; and is an improvement on the construction disclosed 5 in Patent No. 1,616,964 dated February 8, 1927; and the invention has for its object to provide a stronger construction to resist the normal strains of use without the necessity of using heavier stock to increase the size of the catch.

10 A further object of the invention is to provide a construction by which the keeper is pivoted in such a manner as to be supported against strains tending to either close or open the pin slot by having an inside and outside pivotal bearing one in each of the body member of the catch.

With these and other objects in view, the invention consists of certain novel features of construction, as will be more fully described, and particularly pointed out in the appended claims.

In the accompanying drawings:

Figure 1 is a side elevation of my improved safety catch as mounted upon a bar pin or the like.

Figure 2 shows a blank of the body member before being bent into position and slotted.

Figure 3 is a plan view of the body member having been slotted and in spread-out position.

Figure 4 is a central sectional view of Figure 3.

Figure 5 is a plan view of the keeper.

Figure 6 is a sectional view thereof.

Figure 7 is a central sectional view illustrating the body and keeper in certain position which they assume before the ears of the body are closed on the keeper to secure it in position.

Figure 8 is a sectional view of the body and keeper in assembled position.

Figure 9 is an elevation thereof in a position at right angles to that shown in Figure 8 with the keeper in open position.

Figure 10 is a view similar to Figure 9 showing the keeper in closed position in the body.

It is found in the operation of safety catches of the character herein described that 50 a strain in certain directions on the handle member of the keeper tends to close the pin stem receiving slot therein and strains in another direction tends to spread open this slot; and in order to support the keeper in a rotatable bearing to resist such strains a ro-

tatable bearing is formed to both extend inside of portions of the keeper and also to extend outside of portions of the keeper so as to resist both opening and closing strains of the keeper which object is accomplished 60 in the prior patent above referred to of which I am one of the joint inventors, and in accomplishing this result in the patented construction referred to I find that very fine workmanship was necessary to form the 65 groove about the trunnion and further as the keeper was supported entirely by a trunnion extending from one ear only, it was necessary to extend the trunnion entirely through the keeper thereby weakening the same to a certain extent by removing a certain amount of stock, and in order to avoid the disadvantages of this patented construction above referred to and to retain the advantages of the inside and outside bearings, I have formed a recess in one ear of the body portion of the catch and a trunnion on the other ear and to 70 co-operate therewith I have provided a trunnion on one face of the keeper to extend into the recess in one ear and a recess on the other 75 face of the keeper to receive the trunnion on the other ear by which construction it is not necessary to extend the trunnion on the ear entirely across the bridging space between the ears or to remove as much stock from the 80 keeper as in the patented construction heretofore referred to, by which construction I obtain a spaced and increased bearing support for the keeper by which the supporting strength of both ears is utilized and a greater 85 amount of stock is present in the keeper to resist such strains as the same receives; and the following is a detailed description of the present embodiment of this invention and showing one construction of safety catch by 90 which these advantageous results may be accomplished.

With reference to the drawings, 10 designates a bar pin or the like having a pin-stem joint 11 mounted thereon with a pin stem 12 100 pivoted as at 13. A safety catch generally designated 14 receives the pointed end of the pin stem 12 and consists of a body portion 15 having spaced ears 16 and 17 extending therefrom with a keeper 18 rotatably mounted 105 between these ears in the manner to be hereinafter described. Ear 16 is provided with a recess 19 and a trunnion 20 extends from the opposite ear 17. The keeper 18 is recessed as at 21 in one face to rotatably receive 110

the trunnion 20 while its opposite face has a trunnion 22 extending therefrom to be rotatably supported in the recess 19 in the ear 16.

Slots 23 and 24 are provided in the ears 5 of the body member and a slot 25 in the keeper whereby when the keeper is in one position of rotation as illustrated in Figure 9 the slots 23, 24 and 25 register to receive the pin stem 12 and when the keeper is rotated 10 by means of a handle 26 into the position illustrated in Figure 10 the slot 25 is out of registry with slots 23 and 24 whereby the pin stem is held against removal by the safety catch. The keeper is held in its closed position 15 as illustrated in Figure 10 by means of the detent 27 on the keeper which may be snapped beyond the bar 28 extending across the space between the ears 16 and 17.

In the rotation of the keeper to and from 20 its open or closed positions as illustrated respectively in Figures 9 and 10, strain often occurs to either move the parts 29 or 30 of the keeper toward or from each other, which strain is resisted and the parts supported by 25 the rotatable mounting which I have provided. The parts 29 and 30 are prevented from moving toward each other by the trunnion 20 which is rotatably mounted in the recess 21 in the keeper to support the parts 30 29 and 30 against such closing movement and these parts are prevented from moving away from each other by the trunnion 22 on the keeper which is rotatably mounted in the recess 19 in one of the ears.

35 By the provision of rotatable mounting having a bearing in each one of the ears I may extend the trunnion on one ear only a portion of the distance between the ears as is clearly illustrated in Figures 7 and 8 by which a greater amount of stock remains in the 40 keeper than in the patented construction referred to, as will be clearly apparent in Figure 6.

45 It will be apparent from the construction described that I have provided a safety catch which is strong and durable in construction and one which may be made comparatively small and yet possess the required strength for its successful operation.

50 The foregoing description is directed solely towards the construction illustrated, but

I desire it to be understood that I reserve the privilege of resorting to all the mechanical changes to which the device is susceptible, the invention being defined and limited only by the terms of the appended claims. 55

I claim:

1. In a safety catch, a body member having spaced ears, a keeper between said ears, means for rotatably mounting said keeper consisting of a recess in one ear and a projection on the other ear and a cooperating projection on one face of the keeper and a recess in its opposite face to rotatably fit the corresponding oppositely formed parts on the ears and 65 form a bearing to resist either an opening or closing strain on said keeper.

2. In a safety catch, a body member having spaced ears, a keeper between said ears and bearing means for rotatably mounting said 70 keeper in said ears consisting of formations between said keeper and ears to provide for said keeper an inside bearing in one of said ears and an outside bearing in the other of said ears. 75

3. In a safety catch, a body member having spaced ears one of said ears having a recess in the inner face thereof, a trunnion extending from the other of said ears toward said recess and partially bridging the space between said ears, a rotatable keeper having a recess in one face to receive said trunnion and a projection on its opposite face to extend into said recess in said ear to operatively mount said keeper in position. 85

4. In a safety catch, a body member having spaced ears with a radial slot to receive a pin stem, a rotatable keeper positioned between said ears and being slotted to register with the slotted ears in one position of rotation, an arcuate projection extending inwardly from one of said ears, said keeper having a recess of corresponding shape to fit thereover and have a rotatable bearing thereon, an arcuate projection on said keeper and the 90 other of said ears having a recess of corresponding shape to provide a rotatable bearing for said keeper projection, whereby said keeper is provided with rotatable bearing in both of said ears. 95

In testimony whereof I affix my signature. 100
JOHN FIELDING.
